US0D1067039S

(12) United States Design Patent (10) Patent No.: US D1,067,039 S
(45) Date of Patent:  Mar. 18, 2025

(54) BOTTLE

- (71) Applicant: LeChat, Hercules, CA (US)
(72) Inventor: Newton Luu, Hercules, CA (US)
(73) Assignee: LeChat, Hercules, CA (US)
() Term: 15 Years
(21) Appl. No.: 29/792,054
(22) Filed: Mar. 1, 2022

Related U.S. Application Data

- (60) Division of application No. 29/725,330, filed on Feb. 24, 2020, now Pat. No. Des. 944,646, which is a continuation of application No. 29/715,639, filed on Dec. 3, 2019, now Pat. No. Des. 949,019, which is a division of application No. 29/693,110, filed on May 30, 2019, now Pat. No. Des. 868,582, which is a division of application No. 29/644,917, filed on Apr. 20, 2018, now Pat. No. Des. 850,264.

Primary Examiner — Omeed Agilee*Assistant Examiner* — David Truong(74) Attorney, Agent, or Firm — Aka Chan LLPCLAIM

The ornamental design for a bottle as shown and described.

DESCRIPTION

FIG. 1 shows a perspective view of a bottle showing my new design.
FIG. 2 shows a side view of FIG. 1.
FIG. 3 shows a top view of FIG. 1; and,
FIG. 4 shows a bottom view of FIG. 1.

The broken lines in the drawings depict portions of the bottle that form no part of the claimed design.
